Primary Examiner — Kevin K Rudzinski*Assistant Examiner* — Clare Ann Gannon(74) Attorney, Agent, or Firm — ROY KIESEL FORD DOODY & NORTH, APLC(57) CLAIM

The ornamental design for a baby mat, as shown and described.

DESCRIPTION

FIG. 1 is a perspective view of baby mat showing our new design;

FIG. 2 is a top plan view thereof;

FIG. 3 is a bottom plan view thereof;

FIG. 4 is a side view thereof;

FIG. 5 is a rear end view thereof; and,

FIG. 6 is a front end view thereof.

The broken lines shown herein depict an exemplary attachment to the baby mat only; they form no part of the claimed design.
